UNITED STATES PATENT OFFICE.

JOHN BRETZ, JR., OF DETROIT, MICHIGAN.

PISTON-RING REMOVER.

1,303,458.

Specification of Letters Patent. Patented May 13, 1919.

Application filed July 1, 1918. Serial No. 242,761.

To all whom it may concern:

Be it known that I, JOHN BRETZ, Jr., a citizen of the United States of America, residing at Detroit, in the county of Wayne 5 and State of Michigan, have invented certain new and useful Improvements in Piston-Ring Removers, of which the following is a specification, reference being had therein to the accompanying drawings.

10 This invention relates to tools for removing packing rings from pistons and its object is to provide a very simple and efficient device for the purpose which is inexpensive to manufacture and is so constructed as to 15 prevent injury to a ring in removing it and will expand and hold the ring without liability of accidental disengagement therefrom.

With these and other ends in view, the 20 invention consists in the matters hereinafter set forth and more particularly pointed out in the appended claims, reference being had to the accompanying drawing in which

25 Figure 1 is a perspective view of tool illustrative of the invention and showing the same as applied to a ring in use;

Fig. 2 is an edge elevation of the tool;

Fig. 3, an enlarged end elevation showing the same engaged with a piston ring; and

30 Fig. 4, is a perspective detail showing a slightly modified construction for use in removing rings of the type to which the device is shown as applied in the figure.

As shown in the drawings, the tool comprises 35 two thin flat metal strips 1 each curved or bent laterally intermediate its ends so that said middle portions may be overlapped and pivotally united by a bolt 2 passing through openings in the two strips.

40 Each bar or strip 1 is curved or bent laterally toward the other strip at each end so that when the bars are turned on their pivotal connection the adjacent ends of the bars at one end will be brought together and the 45 opposite ends of the bars will be spread apart, the laterally curved portions 3 of the bars between their ends and their pivotal connection, facilitating the pivotal movement by serving as a portion to be grasped in the 50 hand of the operator.

The end portions 4 of the bars are twisted, bringing the planes of their side faces at right angles to the corresponding faces of the body portion so that these end portions 55 may be brought together, face to face, and each end portion of each bar is provided

with a notch to receive the sharp points or angles 5 of a split piston ring 6 which is severed at an angle of approximately thirty degrees to one edge of the ring to overlap 60 when the ends are brought together, the meshing of the end face with one edge forming the acute angle or point 5. In order that the notches 6 and 7 in the opposed ends of the bars may conform closely to the shape of 65 that portion of angular ends of the ring to be engaged thereby, the notch 6 is formed with a beveled upper side 8 and a straight lower side and the notch 7 is formed in a similar manner with the beveled edge 9 at 70 the lower side thereof. The beveled ends of the ring thus seat firmly upon the sides of the notches with their sharp angular points 5 projecting through the notches, and thus 75 said ends are firmly engaged by the tool, preventing accidental disengagement or a tendency of the ring to tilt when the ends are spread apart by the tool. In other words the angular ends of the ring wedge into these notches, and the greater the resistance 80 offered by the ring to spreading, the more firmly it will be held by the tool.

85 Preferably, one end of the tool is formed with notches, as shown, to engage a ring the ends of which are beveled in one direction, and the opposite end with notches arranged to engage a ring, the ends of which are beveled in an opposite direction, so that by simply turning the tool, end for end, it may be 90 used first upon one ring and then upon the other, or the tool may be formed at one end to engage one kind of ring and at the opposite end to engage another kind, and as shown at 10 in Fig. 4, the ends being split 95 longitudinally to form overlapping tongues 11.

100 As shown in Fig. 4, when the tool is made for removing lap-joint rings 10, the ends 12 of the bars 1 are turned outwardly without being twisted as shown in the other figures, and these ends are notched at one side to 105 form shoulders 13 adapted to engage the shoulders 14 on the ring, and projections or tongues 15 to engage the outer face of the ring.

110 Obviously, the ends of the tool may be formed in various ways to properly engage and hold rings of different constructions and I do not therefore limit myself to the particular construction shown.

What I claim is:—

1. A piston ring expander comprising two

metal strips, bent laterally and overlapped intermediate of their ends, both ends of each strip being formed to engage the end of a piston ring, and a pivot connecting the overlapped portions of said strips to form a double ended tool.

2. A piston ring expander comprising two flat metal strips, bent laterally intermediate of their ends with said intermediate portions overlapped, the end portions of said strips at both ends thereof being twisted, to bring the side faces of said end portions into planes at right angles to the planes of the side faces of the intermediate portions of the strips, and both end portions of each strip being formed with notches in their ends to receive and hold the ends of a piston ring, and a pivot connecting said strips at their overlapped portions.

3. A piston ring expander comprising two flat metal strips overlapped and pivotally connected intermediate of their ends, the portions of said strips between their pivotal connection and both ends of each strip being curved laterally in opposite directions to be grasped in the hand and both end portions of each strip being twisted to bring the side faces thereof into planes at right angles to the planes of the side faces of its intermediate portion and each formed with an end notch beveled to conform to the bevel of the end of a piston ring.

In testimony whereof I affix my signature in the presence of two witnesses.

JOHN BRETZ, JR.
